INVENTOR

WITNESS:

Bob P. Kitchel.

Archibald B. Hubbard
by Frank J. Busser
ATTORNEY.

UNITED STATES PATENT OFFICE.

ARCHIBALD B. HUBARD, OF OGONTZ, PENNSYLVANIA.

REINFORCED JOINT.

Application filed June 6, 1921. Serial No. 475,227.

To all whom it may concern:

Be it known that I, ARCHIBALD B. HUBARD, a citizen of the United States, residing at Ogontz, county of Montgomery and 5 State of Pennsylvania, have invented a new and useful Improvement in Reenforced Joints, of which the following is a full, clear, and exact description, reference being had to the accompanying drawings, which 10 form a part of this specification.

This invention relates to an improved means for reinforcing the joint between two adjacent composition board members, or card board members, and more particularly 15 for reinforcing the joint between adjacent members of a card board box or container.

The precise nature of my invention will be best understood by reference to the accompanying drawings, which will now be described, it being premised however, that various changes may be made in the details of construction without departing from the spirit and scope of my invention, as defined 20 in the appended claims.

Fig. 1, of the drawing is a perspective view of one side of one form of joint made in accordance with my invention.

Fig. 2, is a similar view of the other side 30 thereof.

Figs. 3 and 4 are views similar to Figs. 1 and 2 of another form of joint.

Fig. 5 is a face view of another form of reinforcement.

Fig. 6 is a sectional view through a joint such as shown in Fig. 5, in which the members are bent at right angles to each other.

Fig. 7, is a view similar to Fig. 6 of another form of joint.

Figs. 8 and 9 are views of staples such as used in making the joint.

Fig. 10 is a perspective view showing how the staples are bent about the anchoring devices.

In these drawings 2 and 3 designate the two members connected to each other by the reinforcing devices.

The joints shown in Figs. 1, 2, 5, 6 and 7 are reenforced by means of staples shown in 50 Figs. 8 and 9, having body members 4 and a leg 5 at each end thereof, which extends at right angles to the body. These legs may be plain as shown in Fig. 8, or crimped as shown in Fig. 9.

Where possible I reinforce the joint before bending, as shown in Fig. 5, and then

bend the numbers 2 and 3 relative to each other, to the positions shown in Figs. 1 to 4, 6 and 7.

In reinforcing joints as above described, 60 the card board is first scored in the usual manner along the line 6, as indicated by the dot and dash line in Fig. 5, if the members 2 and 3 are formed from an integral piece, or two pieces are placed edge to edge. The 65 legs 5 of the staples are then passed through the bodies of members 2 and 3 and are bent about anchoring devices 7 so as to form crimps in the legs as shown. The one member is then bent to a position at right angles 70 to the other along the line 6, or along the adjacent edges of the members 2 and 3, and when bending, the staples as well as the anchoring means are simultaneously bent when either of said members extend across the 75 junction between the members 2 and 3.

In Figs. 1 and 2, the anchoring means 7, extends back and forth across the junction, and in this case both staples and reinforce 80 are bent when the one member is bent relative to the other.

In Figs. 5 and 6 the anchors 7 consist of straight wires, which extend parallel to the line of the junction between the members.

The anchor 7 in the form shown in Fig. 7 85 consists of a perforated sheet metal plate, through which the legs 5 extend, and in which case I prefer to kink the legs as indicated at 8, so as to increase the resistance against withdrawal of the staples. In the 90 remainder of the forms shown this resistance is increased by kinking the legs about the wire anchor.

If desired this resistance may be further increased by corrugating the legs 5, as indicated in Fig. 9.

In the form shown in Figs. 3 and 4 the joint is reenforced by an external plate 9 through which the staples extend. In this form the staples do not extend across the 100 junction between the members 2 and 3, there being one set of staples which extend through the plate 9 and the member 2, while another set extends through the plate 9 and the member 3.

The plate anchor 7 of Fig. 7 and the plate 9 of Figs. 3 and 4, reinforce the joints against compression stresses, as they form columns when in a vertical position and beams when in a horizontal position.

The advantages of my invention result from the provision of a reenforced joint

formed of a plurality of separate wires or staples, the legs of which are bent about anchoring means which will prevent the ends or legs being pulled through the body of the members, as well as the provision of means for reinforcing the joint against compression and extension stresses, both transverse and longitudinal.

I claim:

- 10 1. A reinforce for a joint between two members having staples provided with legs which extend through the members, and anchoring means with which the legs are crimped.
- 15 2. A reinforce for a joint between two members, comprising devices having body portions and legs which extend through the members and anchoring means on the sides

of the members opposite the sides on which the bodies of the devices are located, with 20 which the legs are crimped.

3. A reenforced joint between two box forming members, comprising devices having body portions on one side of each member and legs which extend through the 25 members, and anchoring devices on the sides of the members opposite the sides engaged by said body members, said legs being crimped into engagement with said anchoring devices, one of said devices extending 30 across the joint.

In testimony of which invention, I have hereunto set my hand, at Philadelphia, on this day of June, 1921.

ARCHIBALD B. HUBARD.
